(57) **CLAIM**

A new and original design for a trellis post, as shown and described.

DESCRIPTION

FIG. 1 is a perspective view from an end and one side thereof;

FIG. 2 is an end view thereof;

FIG. 3 is a side view thereof;

FIG. 4 is an opposite side view thereof;

FIG. 5 is a top view thereof; and,

FIG. 6 is a bottom view thereof.

In FIGS. 1, 3, 4, 5 and 6, the trellis post is interrupted in order to illustrate that the design is of indefinite length.
